UNITED STATES PATENT OFFICE.

WALTER D. BUTZ, OF NORRISTOWN, PENNSYLVANIA, ASSIGNOR TO PARAMOUNT
HOSIERY FORM DRYING CO., OF CHICAGO, ILLINOIS, A CORPORATION OF ILLINOIS.

STOCKING-DRYING FORM.

1,207,497.

Specification of Letters Patent.

Patented Dec. 5, 1916.

Application filed July 10, 1915. Serial No. 39,123.

To all whom it may concern:

Be it known that I, WALTER D. BUTZ, a citizen of the United States, residing in Norristown, Pennsylvania, have invented certain Improvements in Stocking-Drying Forms, of which the following is a specification.

One object of my invention is to so construct a stocking drying form that the length of the foot portion thereof or the width of the leg portion can be varied without materially changing the conformation of said foot and leg portions in other respects, and another object is to effect the widening of the leg portion without, at the same time, widening the foot. These objects I attain in the manner hereinafter set forth, reference being had to the accompanying drawings, in which—

Figure 1 is a side elevation, partly in section, of a stocking drying form constructed in accordance with my invention; Fig. 2 is a horizontal section on the line *a—a*, Fig. 1; Fig. 3 is a horizontal section on the line *b—b*, Fig. 1; Fig. 4 is an enlarged side elevation of the foot and ankle portions of the form showing the foot portion contracted to its fullest extent; Fig. 5 is a similar view showing the foot portion lengthened to its fullest extent; Fig. 6 is a transverse section on the line *c—c*, Fig. 4; Fig. 7 is a transverse section on the line *d—d*, Fig. 4; Fig. 8 is a view looking in the direction of the arrow *x* Fig. 4; Fig. 9 is a view looking in the direction of the arrow *y* Fig. 5; Fig. 10 is a transverse section on the line *e—e*, Fig. 5; Fig. 11 is a transverse section on the line *f—f*, Fig. 5; Fig. 12 is a perspective view on a reduced scale showing, separated from one another, the stationary and adjustable members of the foot portion of the form, and Fig. 13 is a section on the line *g—g*, Fig. 5.

The drying form may be constructed either of wood or metal, or with a metal foot portion and a wooden leg portion, and the metal portion may be internally chambered or channeled, as shown for instance by dotted lines in Figs. 2, 3, 4, 6 and 7, for the reception or circulation of steam or other heating agent.

The form comprises a foot portion 1 and a leg portion 2 as usual, but the foot portion has an extensible toe member 1^a so that

it can be shortened or lengthened, as shown, respectively, in Figs. 4 and 5, and the leg portion has an extensible front member 2^a so that it can be narrowed or widened, as shown, respectively, by full and dotted lines, or by dot-and-dash lines in Fig. 1.

The foot portion of the form has central longitudinal slots at top and bottom as indicated at 3, these slots communicating at the toe end of the foot portion with a connecting slot 4 and the leg portion of the form has in the front of the same a central vertical slot 5 for the reception of the front member 2^a which is pivoted at its lower end at the base of the ankle portion of the leg, as shown at 6 in Fig. 1, the member 2^a and the slot 5 for the reception of the same, gradually increasing in depth from the lower to the upper end, as shown in Fig. 1, so that by drawing forwardly the front member 2^a a gradual increase in the width of the leg portion of the form, from the foot to the top may be effected, as shown by dot-and-dash lines in Fig. 1, without in any way affecting the shape of the foot portion of the form.

The extensible toe member 1^a of the foot has upper and lower wings 7 fitted to the upper and lower slots 3, the main web 8 of the toe member entering the slot 4 at the forward end of the foot so as to properly guide the toe member 1^a in its forward and backward movements. Said member 1^a may be further guided and steadied in its movements by providing each of the slots 3 with a forwardly projecting tenon 11 adapted to engage a mortise 12 in the upper or lower tongue 7 of the toe member, and by one or more steady pins 13 (Figs. 5 and 11) carried by the toe member 1^a and entering openings in the foot member 1, as shown in Fig. 5, or the reverse.

The main web 8 of the toe member 1^a of the form has therein recesses for the reception of springs 9 which bear against the base of the slot 4 and serve to project the toe member 1^a so as to cause the foot portion of the form to adapt itself to stocking feet of different lengths. Removal of the toe member 1^a from the foot portion 1 of the form may be prevented by means of a transverse screw or pin 10 adapted to a slot 10^a formed in the web 8 of the toe member, as shown for instance by dotted lines in

Fig. 4, or the toe member 1^a may, if desired, be held in different positions of forward adjustment by adapting the pin 10 to either of a series of notches 10^b in the slot 10^a, as shown in Fig. 5, the foot portion 1 of the form being slotted vertically, as shown in Figs. 5 and 10, to permit movement of the pin 10 sufficient to carry the same into and out of said notches 10^b.

10 The extensible front member 2^a of the leg portion of the form may also be locked in different positions of adjustment by means similar to those employed for locking the toe member 1^a, or other means for thus locking the extensible toe and leg members in their different positions of adjustment may be adopted without departing from the essential features of my invention.

I am aware that in the patent of R. N. 20 Chandler No. 81,981, dated September 8, 1868, there is shown a stocking drying form having leg and foot portions adjustable as to width, and a longitudinally adjustable toe member, but in said patented device the parts 25 were so constructed and combined that the widening of the leg could not be effected without a corresponding widening of the foot, and there was a break in the straight line longitudinal continuity of the upper 30 and lower edges of the foot in all positions of the toe member, whereas my stocking drying form is free from both of these objections.

I claim:—

35 1. The combination of the foot portion of a stocking drying form, with an extensible toe member slidably mounted in respect to said foot portion and adjustable in the axial line thereof, said toe member having its top 40 and bottom edges in line with the corresponding edges of the foot portion in the different positions of adjustment of said toe member, and means acting on the toe member to effect its movement on the foot-portion.

50 2. The combination of the foot-portion of a stocking drying form, an extensible toe-member slidably mounted in respect to the foot-portion and having a projecting wing, the foot-portion being provided with a slot 55 for the reception of said wing, and elastic means distinct from but associated with the foot-portion and the toe-member for resisting a compressing action thereon of hosiery stretched thereover.

60 3. The combination of the foot-portion of a stocking drying form, an extensible toe-member slidably mounted in respect to the foot-portion and having a projecting wing formed with a mortise therein, the foot member being provided with a slot and a 65 projecting tenon for entering the mortise in the wing, and means normally active on the toe-member and tending to effect a sliding of it in respect to the foot-portion.

4. The combination of the foot portion of a stocking drying form with an extensible toe member slidably mounted in respect to said foot portion, said toe member having top and bottom wings and the foot portion of the form having top and bottom slots for the reception of said wings, and means normally active on the toe-member to resist an inherent compressing action thereon of hosiery stretched thereover.

70 5. The combination of the foot portion of a stocking drying form with an extensible toe member slidably mounted in respect to said foot portion, said toe member having top and bottom wings and the foot portion of the form having top and bottom slots for the reception of said wings, and said slots having forwardly projecting central tenons therein and the wings of the toe member having central mortises for the reception of 80 said tenons.

85 6. The combination of the foot portion of a stocking drying form with an extensible toe member slidably mounted in respect to said foot portion, and elastic means tending to project said toe member.

90 7. The combination of the foot portion of a stocking drying form with an extensible toe member slidably mounted in respect to said foot portion, elastic means tending to project said toe member, and means for restricting such projection.

95 8. The combination of the foot portion of a stocking drying form with an extensible toe member slidably mounted in respect to 100 the foot portion, elastic means for projecting said toe member, and means for locking said extensible toe member in different positions of adjustment in respect to the foot portion of the form.

105 9. The combination of the foot portion of a stocking drying form, with an extensible toe member slidably mounted in respect to the foot portion, toe-projecting means normally active on the toe-member, and a steady 110 pin guiding said toe member in its movements.

115 10. A stocking drying form including in combination, a foot-portion provided at its edges with longitudinal grooves, an extensible toe-member provided with wings slidably mounted in and partially embraced by the walls of said grooves, the exposed faces of said winged toe-member, adjacent said grooves, being practically flush with the exterior wall of the foot-portion to present a substantially smooth hosiery-engaging surface, and means associated with said toe-member and foot-portion and having a normal tendency to adjust the toe-member and thereby effect a change in the effective drying area of the form.

120 11. A hosiery drying form including in combination a foot-member, and an extensible toe-member; one of said members being 125

provided with longitudinal grooves adjacent to its edges, while the other member is provided with wings adapted to slide in said grooves and be partially embraced by the walls thereof; the exposed portions of said wings being practically flush with the faces of said groove member; the edges of said wing and groove members converging to form crease-producing surfaces, and means associated with said foot and toe-members and having a normal tendency to effect a separating action therebetween to change the heating area of the form.

12. A hosiery drying form including a foot-portion and an extensible toe-portion adjustably mounted in respect to the foot-portion, and elastic means associated with but independent of said portions and acting thereon to effect a movement of one portion in relation to the other tending to project said toe-member.

13. As an article of manufacture, a hosiery drying and shaping device comprising a leg-portion and a foot-portion, the latter comprising a plurality of sections, and means associated with said foot-sections and adapted to effect its longitudinal movement in relation to, and within the plane of, the other, whereby said foot-portion may be elongated with a hosiery article thereon without distorting the foot-portion of the article transversely.

14. As an article of manufacture, a hosiery drying and shaping device comprising a leg-portion and a foot-portion, the latter comprising a plurality of sections, one of which has longitudinal movement in relation to, and within the plane of, the other, whereby said foot-portion may be elongated with a hosiery article thereon without distorting the foot-portion of the article transversely, and means associated with but distinct from said foot-sections for automatically actuating the movable section of said foot-portion.

15. As an article of manufacture, a hosiery drying and shaping device comprising a leg-portion and a foot-portion, the latter comprising a plurality of sections, one of which has longitudinal movement in relation to, and within the plane of, the other, whereby said foot-portion may be elongated with a hosiery article thereon without distorting the foot-portion of the article transversely, and means associated with but distinct from said sections for automatically actuating the movable section of said foot-portion for effecting an elongation of said foot-portion.

16. As an article of manufacture, a hosiery drying and shaping device comprising a leg-portion and a foot-portion, the latter comprising a plurality of sections, one of which has longitudinal movement in relation to, and within the plane of, the other, whereby said foot-portion may be elongated

with a hosiery article thereon without distorting the foot-portion of the article transversely, resilient means associated with but distinct from the sections for automatically actuating the movable section of the foot-⁷⁰ portion.

17. A hosiery drying form including a foot-portion, an extensible toe-portion movably mounted thereon, and means interposed between the two portions having a normal ⁷⁵ tendency to adjust the toe-portion and thereby elongate the area of the form.

18. A hosiery drying and stretching form including a relatively stationary foot-portion having a heel-section, a toe-portion extensibly mounted on the foot-portion and having movement longitudinally thereof, and means interposed between the two portions and having a normal tendency to displace the toe-portion away from the heel-section and thereby stretch and simultaneously ⁸⁵ shape the foot-portion of the hosiery dried thereon.

19. A hosiery drying and shaping form, hollow to contain a heating medium and ⁹⁰ comprising a relatively stationary foot-portion including a heel-section and having relatively reduced crease-producing edges, a toe-portion extensibly mounted on the foot-portion and having a movement longitudinally thereof and having relatively reduced crease-producing edges alining with the the creasing-producing edges of the foot-portion, and means acting on the toe-portion to displace it away from the heel-section and thereby effect a stretching of the hosiery while being dried on the form.

20. A hosiery drying and shaping form, hollow to contain a heating medium to heat it from within, and comprising a foot-portion, a toe-portion movably mounted thereon, and resilient means acting on the toe-portion and tending to resist the compressing action of hosiery stretched thereon.

21. A hosiery drying and shaping form, hollow to contain a heating medium to heat it from within, and comprising a foot-portion including a heel-section and having relatively reduced crease-producing edges, a toe-portion extensibly mounted on the foot-portion and also having relatively reduced crease-producing edges in substantial alinement with the crease-producing edges of the foot-portion, and means acting on the toe-portion as a resistant to the compressing action of hosiery stretched thereon.

22. A hosiery drying and shaping form, hollow to contain a heating medium to heat it from within, and comprising a foot-portion having relatively reduced crease-producing edges, a toe-portion extensibly mounted thereon and having similar crease-producing edges and having heat-absorbing sections in constant engagement with the heat-radiating surfaces of the foot-portion, ¹²⁵ ¹³⁰

and yielding means acting on the toe-portion and tending to resist the compressing action of hosiery stretched thereon.

23. A hosiery drying form including a 5 foot-portion, an extensible portion movably mounted thereon, and means associated with said portions and having a normal tendency to adjust the extensible portion bodily in relation to the foot-portion and thereby 10 change the exterior area of the form.

24. A hosiery drying form including a foot-portion having its sides converging and terminating in crease-producing edges, an extensible portion bodily movable thereon

and also having its sides converging and terminating in crease-producing edges, and means associated with the two portions and having a normal tendency to adjust one in relation to the other and thereby change the exterior area of the form. 15

20 In testimony whereof, I have signed my name to this specification, in the presence of two subscribing witnesses.
